UNITED STATES PATENT OFFICE.

CLYDE S. MASON, OF BUFFALO, NEW YORK.

RETORT COKE-OVEN.

SPECIFICATION forming part of Letters Patent No. 782,259, dated February 14, 1905.

Application filed May 31, 1904. Serial No. 210,487.

To all whom it may concern:

Be it known that I, CLYDE S. MASON, a resident of Buffalo, in the county of Erie and State of New York, have invented a new and useful 5 Improvement in Retort Coke-Ovens; and I do hereby declare the following to be a full, clear, and exact description thereof.

My invention relates to retort coke-ovens; and its object is to secure a more uniform distribution of the gases around the ovens and to equalize this distribution when necessary, so as to uniformly coke the charge of coal.

In the accompanying drawings, Figure 1 is a horizontal section through my improved 15 oven, the section being taken partly through the ovens and partly through the combustion-chambers below the ovens, said section being indicated by the line 1 1 on Fig. 4. Fig. 2 is a vertical section through an oven transversely 20 through the regenerators, said section being indicated on the line 2 2, Fig. 1. Fig. 3 is a similar section taken through the vertical flues in the side walls of the ovens, said section being indicated on the line 3 3, Fig. 1; 25 and Fig. 4 is a vertical section transversely through the ovens and lengthwise of a regenerator, said section being taken on the line 4 4, Fig. 1.

A well-known type of retort coke-oven in 30 quite extensive use is known as the "Hoffmann" or the "Otto-Hoffmann" oven, this comprising a battery or series of horizontal retort-ovens with vertical heating-flues between the walls of adjacent ovens, which heating-flues at 35 their lower ends communicate with combustion-chambers located below the ovens and at their upper ends communicate with a horizontal flue connecting the two sides of the series of ovens. The combustion-chambers at each 40 side of the battery communicate with a regenerator located underneath or at some point adjacent to that side of the battery and in which the air is heated prior to entering the combustion-chamber, where it is mingled with 45 the gas. In the operation of these ovens the air enters first through the regenerator on one side of the battery, is heated therein, thence passes up into the combustion-chambers on that side, where it is mingled with the gas 50 and burned, the heated products of combus-

tion passing up through the vertical heating-flues between the walls of adjacent ovens, thus heating the latter, thence by means of the horizontal flue over to the other side of the battery of ovens, down through the vertical flues and through the regenerator on that side, and thence to the stack, the waste heat thus heating the checker-work in the last-named regenerator. After a certain period of operation—say about thirty minutes—the 55 course of the air and gas through the regenerators and oven is reversed, as is well known, the newly-heated regenerator serving to heat the incoming air, while the other regenerator is reheated by the waste products 60 of combustion. The objection to this type of oven is that the heated gases rising from the combustion-chambers are not equally distributed through the vertical flues, neither is there any way of equalizing or regulating the 65 flow of gases through the vertical flues so as to uniformly distribute the same. As a result, the charge of coal in the coking-ovens is not uniformly coked. My invention improves on this type of oven by providing 70 means for equalizing the distribution of the hot gases in the vertical heating-flues so as to uniformly coke the coal. This I attain by providing above the vertical flues one or more horizontal flues in addition to the horizontal 75 flue which is in use with the Hoffmann oven for carrying the gases from one side of the battery to the opposite side, which additional horizontal flue or flues extend from the central line of the battery out to the sides thereof, and the walls between said horizontal flues 80 being provided with openings which are controlled by regulating-dampers.

In the accompanying drawings I have shown my invention applied to a Hoffmann oven substantially the same as that shown in United States Patent No. 492,400, granted February 28, 1893, to Gustav Hoffmann. I have not deemed it essential to show all of the details of said oven, as the same will be readily understood by reference to the patent above named, or by those familiar with ovens of this type.

The coking-ovens are formed as long narrow chambers 1, built up by masonry and extending from side to side of the masonry 100

structure. These ovens are closed at their ends 2 by means of gas-tight doors. The coal is supplied through openings 3 through the top wall of the ovens, which openings are 5 also closed by gas-tight doors, or the coal may be introduced in compressed cakes through the doors 2. The gas developed by the coking of the coal is led away by pipes 4 and conduit 5 to the condenser. (Not shown.)

10 When the gas has been cooled off in the condenser and separated from the tar and ammonia, it is returned to the oven for combustion, or gas produced in some other way is supplied to the oven for combustion. The gas is

15 returned from the condenser or other source through the conduit 6 and is conducted alternately into the supply-pipes 7 and 8, which are controlled by suitable valves 9 and 10, the position of these valves determining into

20 which pipe the gas enters. From these pipes the gas passes through the small branch pipes or burners 11 and 12 into the combustion-chambers 13 and 14, in which it is burned. The air for the combustion of the gas is forced

25 by any suitable apparatus through the conduit 15 and by an ordinary reversing or deflecting damper 16 of the butterfly or other type is diverted either into the canal 17 or the canal 18. These canals lead, respectively,

30 to the two regenerators 19 and 20, which are located below or at some point adjacent to the combustion-chambers and which are filled with checker-work, as is common. The air passes through one of these regenerators, is heated

35 therein, and then enters, by means of flues 21, into the combustion-chambers on that side of the battery wherein it is mixed with the gas and burned. The hot products of combustion pass from the combustion-chambers through

40 ports 22 into the vertical heating-flues 23, located in the walls between adjacent ovens, thus heating the latter. Above these vertical flues 23 and also in the walls between adjacent ovens are the horizontal flues 24, which lead

45 over to the opposite side of the battery. As a result, the air and gas are burned on one side of the battery, pass up through the vertical flues 23 on that side, thence by means of the horizontal flues 24 over to the opposite side

50 of the battery, down through the vertical flues 23, and into the regenerator on that side of the furnace, heating the checker-work therein, and thence through the canal 17 or 18, as the case may be, to the stack. Periodically the re-

55 versing-valve is shifted and the gas-valves 9 and 10 are changed—that is, the one closed and the other opened. The course of the air and gas is then through the furnace in the opposite direction, as will be readily understood.

60 The oven so far described is or may be of the usual type and is substantially the same as shown and described in Patent No. 492,400, above referred to. In such ovens only a single horizontal flue 24 is used above each

65 series of vertical flues 23, and this is marked c

on Fig. 2 of Patent No. 492,400. With such arrangement there is liability of more of the heated gases flowing up through some of the vertical flues 23 than through others, thus producing the unequal distribution of gases 70 and corresponding non-uniformity in the coking above referred to. My invention is applied at this point. It consists in providing one or more additional horizontal flues above the vertical flues 23. On the drawings I have 75 shown two such additional horizontal flues 25 and 26, respectively, although only one or more than two might be used, if desired. These flues preferably extend from the median line or wall 27 of the battery out to the 80 sides thereof, so that all gases will eventually have to pass through the upper flue 24 in order to reach the opposite side of the battery. The walls 28 and 29, which separate the several horizontal flues, are provided with a series of openings 30, the number of which may be varied; but preferably there will be three such openings arranged substantially as shown—that is, in the lower wall 28 there will be an opening substantially at the middle 85 and one at each end thereof, whereas with the upper wall 29 there will be an opening at the outer end and two intermediate the ends, but none at the inner end thereof. The openings in the walls 28 and 29 are preferably out 90 of line with each other, so that the flow of gases can be more easily equalized. If only one additional flue is used, it will correspond with the flue 25, and the openings and valve arrangement will be the same as shown in the 95 wall 29. If more than two additional flues are used, all of the walls below the upper one will preferably have the same openings and valve arrangement as shown in the wall 28. These additional horizontal flues and the 100 various openings therethrough serve to distribute and equalize the flow of the gases through the vertical flues 23. Preferably the openings through the horizontal walls will be 105 regulated by means of suitable valves, so that the flow of gases can be equalized as far as possible. These valves may be of any type, those shown being ordinary refractory brick or blocks 31, resting on the upper surfaces of the walls and the position of which can be 110 changed by inserting a suitable bar 33 through openings 32 in the side walls. These openings also serve as observation or peep holes and may be used by introducing additional 115 gas-burners, as may be desirable at times, as 120 when speeding the ovens.

In the operation of my oven the air and gas will be periodically reversed and will flow through the oven in exactly the same way as in the well-known Hoffmann oven, the only 125 difference being in providing the one or more additional horizontal flues, together with openings and regulating-valves in the walls separating the horizontal flues, so that the flow of the hot gases through the vertical 130

flues can be equalized and uniform coking of the coal in the adjacent ovens be produced. As above stated, the number of these additional flues is not essential, neither is the 5 precise arrangement of openings through the walls separating the flues shown in the drawings absolutely essential. These details may be varied within wide limits without departing from the spirit of my invention.

10 o What I claim is—

1. In a retort coking-oven, the combination of a series of horizontal retort-ovens, combustion-chambers below the same, vertical heating-flues arranged between adjacent ovens and 15 communicating at their lower ends with the combustion-chambers, and a plurality of horizontal flues between adjacent ovens, one of said flues communicating with the upper ends of the vertical flues and another of said flues 20 extending from side to side of the series of ovens, the wall or walls separating said horizontal flues being provided with openings for equalizing the flow of the gases.

2. In a retort coke-oven, the combination 25 of a series of horizontal retort-ovens, combustion-chambers below the same, vertical heating-flues between adjacent ovens and communicating at their lower ends with the combustion-chambers, a plurality of horizontal flues 30 between adjacent ovens, one of said flues communicating with the upper ends of the vertical flues and another of said flues extending from side to side of the series of ovens, the wall or walls separating said horizontal flues 35 being provided with openings, and regulating valves or dampers for said openings.

3. In a retort coke-oven, the combination 40 of a series of horizontal retort-ovens, combustion-chambers below the same, vertical heating-flues between adjacent ovens and communicating at their lower ends with the combustion-chambers, a plurality of horizontal flues 45 between adjacent ovens, one of said horizontal flues communicating with the upper ends of the vertical flues and another of said flues extending from side to side of the series of ovens, the wall or walls separating said horizontal flues being provided with openings, refractory blocks for regulating the size of said 50 openings, and holes in the oven-wall for the insertion of a rod for moving said blocks.

4. In a retort coke-oven, the combination 55 of a series of horizontal retort-ovens, combustion-chambers below the same, vertical heating-flues between adjacent ovens and communicating at their lower ends with the combustion-chambers, and three horizontal flues between adjacent ovens, the lower one of said flues communicating with the upper ends of 60 the vertical flues and the upper one of said

flues extending from side to side of the series of ovens, the walls separating said flues being provided with openings out of line with each other whereby the flow of gases is equalized.

5. In a retort coke-oven, the combination 65 of a series of horizontal retort-ovens, combustion-chambers below the same, regenerators adjacent to said combustion-chambers and communicating therewith, vertical heating-flues between adjacent ovens and communicating 70 at their lower ends with the combustion-chambers, a plurality of horizontal flues between adjacent ovens, one of said horizontal flues communicating with the upper ends of the vertical flues and another of said horizontal flues extending from side to side of the series of ovens, and the wall or walls separating 75 said horizontal flues being provided with openings for regulating the flow of gas through the vertical flues.

6. In a retort coke-oven, the combination 80 of a series of horizontal retort-ovens, combustion-chambers below the same, regenerators adjacent to said combustion-chambers and communicating therewith, vertical heating-flues between adjacent ovens and communicating 85 at their lower ends with the combustion-chambers, a plurality of horizontal flues between adjacent oven-walls, one of said flues communicating with the upper ends of the vertical flues and extending from the median line of the series of ovens to the side thereof, and another of said flues extending from side to side of the series of ovens, the wall or walls separating 90 said horizontal flues being provided with openings, and regulating dampers or valves for said openings.

7. In a retort coke-oven, the combination 95 of a series of horizontal retort-ovens, combustion-chambers below the same, regenerators 100 adjacent to said combustion-chambers and communicating therewith, vertical heating-flues between adjacent ovens and communicating at their lower ends with the combustion-chambers, three horizontal flues between 105 adjacent ovens and located one above the other, the lower one of said flues communicating with the upper ends of the vertical flues and the upper one of said horizontal flues extending from side to side of the series of ovens, and gas-equalizing openings through the walls 110 separating said flues, said openings being in different vertical planes.

In testimony whereof I, the said CLYDE S. MASON, have hereunto set my hand.

CLYDE S. MASON.
